LOCKER LATCH

Henry C. Baker and Robert H. Peterson, Canton,
Ohio, assignors to Republic Steel Corporation,
Youngstown, Ohio, a corporation of New Jersey

Application April 6, 1934, Serial No. 719,344

10 Claims. (Cl. 292—33)

This invention relates to latch mechanism for lockers and the like such as illustrated in the patent to S. S. French No. 1,729,038, dated September 24, 1929, and may be considered in the nature of an improvement on, or as an alternative form of latch construction with respect to that disclosed in said patent.

The principal object of the invention is to provide latch mechanism particularly adapted for doors of steel lockers which operates easily, quietly and smoothly and results in a relatively snug door closure and which at the same time is strong and rugged and easily assembled and disassembled and may be economically manufactured.

15 The latch assembly of the patent above noted embodies a channel-shaped latching bar which is formed with slots which engage the keeper hook when the locker door is closed. Since the bar is preferably formed of sheet metal, slamming or rough handling of the door has a tendency to mutilate and distort the metal adjacent the hook slots; and one of the features of the present invention is the provision of a latch assembly which overcomes this objection.

20 Another object of the invention is to provide latching mechanism for doors of steel lockers which will automatically effect easy and smooth latching of the door when the latter is closed or urged to closed position regardless of whether or 25 not the door has been previously locked by a key or padlock or both and which will thereafter necessitate the use of the key to permit unlatching of the door.

The various objects and advantageous features 30 of the invention will become apparent in view of the following description taken in conjunction with the drawings, wherein:

Figure 1 is a front elevation of a locker having the present improved latch mechanism applied thereto;

Fig. 2 is a fragmentary sectional view taken on the line 2—2, Fig. 1;

Fig. 3 is a sectional view of the latch bar and reinforcement which serves as a housing therefor taken substantially on the line 3—3, Fig. 1;

Fig. 4 is a cross section taken on the line 4—4, Fig. 3;

Fig. 5 is a detail perspective view of the door handle;

Fig. 6 is a fragmentary cross sectional view of the door and adjacent portions of the locker taken substantially on the line 6—6, Fig. 1;

Fig. 7 is a fragmentary perspective view of the upper extremity of the latch bar and the reinforcing housing therefor;

Fig. 8 is a detail perspective view of the latch bar;

Fig. 9 is a detail perspective view of one of the latch guides and a fragment of the latch bar adjacent thereto;

Fig. 10 is a fragmentary sectional view taken on the line 10—10, Fig. 3.

Referring to the drawings in detail, the locker includes a sheet metal door frame 5 having a door 6 hinged thereon at 7. The door 6 is formed at one of its side edges with a tubular reinforcement consisting of spaced box-flanges 8a and 8b each of which includes inner legs 9 and outer legs 10, and an intervening connecting web 11. The upper and lower extremities of the connecting web 11 and portions of the legs 9 of the box-flanges are cut away to provide guideways or slots 12 and 13 and stops 12a and 13a, note particularly Fig. 3. The edge portion of the leg 10 of the box-flange 8b may be spot welded or otherwise secured to the rear face of the door as shown in Fig. 6. The tubular reinforcement (which serves as a housing and guide for the latch bar as will hereinafter appear) has extended over the top and bottom thereof cover flanges 14 and 15, which are shaped from the metal of the door, the upper and lower extremities of the reinforcement or housing being cut away between the legs 10 to provide a recess 16 for a filler and cushioning block 16a, whose function will be hereinafter made apparent. At an intermediate portion, web 11 is provided with a slot 17 which also extends through the door panel (note Fig. 10) to accommodate a finger lift bar 29, hereinafter referred to, and a hole or opening 18 to provide for attachment of the door handle, said opening 18 also extending through the door panel.

The latching mechanism includes a channel or latch bar generally indicated at 19, the flanges 19a and 19b of which are formed at their opposite extremities with laterally projecting wings 20, which have limited movement in the guideways 12 and 13 when the latch bar is assembled in its housing. The flanges of the channel or latch bar are also provided with spaced bosses 21 which facilitate vertical sliding movement of the bar. The flange 19a of the channel bar is formed with a slot 22, which serves to receive the bolt of a key lock 23 to lock the channel bar against latch releasing movement, note Figs. 1 and 2. The web 19c which connects the channels 19a and 19b of the bar 19 is formed with spaced slots 24 which accommodate latch hooks 25, each of the latter having a shank 25a of substantially U-shaped contour which is secured to

the door frame 5, as by rivets 25b, note Fig. 6. The inner side of the hook notch is cut away as at 25c to provide clearance.

In the patent above noted, the latch hooks engage the metal adjacent the slots formed in the channel or latch bar. The present construction differs in that the latch or channel bar 19 has secured thereto a plurality of latch guides 26, which may be secured to said bar in any suitable manner. In the construction shown, they are formed with laterally-projecting ears or lugs 26a which are welded to the side flanges 19a and 19b of the bar 19, note Fig. 9. In each of these guides a latch bolt 27 is mounted for vertical sliding movement, note particularly Fig. 3. At its upper extremity, each of the latch bolts 27 is turned at right angles as at 27a and abuts against the top of the guide 26. A spring 28 is connected at its lower extremity to the latch guide 26, and at its upper extremity to the outwardly projecting abutment portion or lug 21a of the latch bolt 27. At its lower end the latch bolt 27 is tapered to provide a cam surface which is adapted to contact the cam portion 25a of the latch hook 25.

It will be noted that when the latch or channel bar is assembled in its housing, it has limited vertical movement bodily, while each of the latches or latch bolts 27 are permitted independent vertical movement against the tension of the springs 28, resulting in an advantage which will be hereinafter referred to.

The channel or latch bar has secured to an intermediate portion thereof a combined finger lift and lock lug or bar 29 formed with a hole or opening 30 for a padlock. The finger lift 29 is preferably provided with a boss or projection 29a adapted to engage in an anchor hole formed in the web 19c of the bar 19. The sides of the lift bar 29 are grooved or recessed to permit the said bar to engage in the narrow guide portion of the slot 17, note Fig. 10. A transverse pin 29b serves to fix the finger bar 29 to the side walls 19a, 19b of the channel bar 19. Above the slot 17 a door handle, generally indicated at 32, is secured to the door panel. This handle is shown more or less in detail in Fig. 5, and its lower extremity is formed with a finger guard which is recessed as at 32a, in which recess the lift bar 29 has movement. The inner face of the handle 32 is formed with a boss or projection 33 and a screw hole 34. To attach the handle to the door, it is only necessary to insert the projection or boss 33 in the slot 18 and apply screw 35.

An example of how the parts of the latch mechanism may be assembled is as follows:

Prior to assembling the channel or latch bar 19 in its housing, the finger lift 29 may be connected thereto and the latch bolts 27 inserted in the guides 26 and springs 28 connected to the latch bolts. When inserting the channel lock or latch bar 19 in its housing, it may be held at an angle or incline and the wings 20 at the lower end of the bar inserted in the recess 16 at the lower end of the housing and the bar raised up and tipped forward to bring the upper wings into the upper recess 16, the lift 29 being inserted in the wide portion of slot 17 when the bar is moved into its housing. The channel bar 19 is then lowered until the lower end thereof abuts the lower cushioning block 16a, the upper wings entering the slots 12. The latch hooks 25 may then be attached to the frame 5. When the channel bar 19 is in assembled position, the wings 20 have limited travel in the guideways 12

and 13, the cushioning blocks 16a serving as bumpers for the upper and lower ends of the bar and ensuring a quiet action.

It will be noted that the improved latch mechanism will automatically latch when the door is pushed towards closed position, the tension of the springs 28 preferably being such as to permit the latch bolts 27 to slide vertically substantially independently of the channel bar when the said bolts engage the cam portion 25a of the hooks 25. In the event that the latch mechanism is locked by either or both the key lock 23 and padlock when the door is open, the door may be pushed or slammed shut and become automatically locked in closed position. To open the door, it is only necessary to grasp the trigger handle 32 and lift bar 29 and slide the channel bar and latch bolts vertically clear of the latch hooks 25. The handle 32 has an attractive appearance and conceals the lift bar 29 by the depending skirt 20 at the lower portion of the handle. The entire assembly may be economically manufactured and assembled. When it is required to lock the door of the locker the aperture 30 in the lift bar 29 is provided to accommodate the shackle or hasp 25 of a padlock or any other suitable locking means which will prevent the lift bar 29 from being elevated to raised position.

It will be understood that certain minor changes and modifications in structure may be adopted within the scope of the invention as defined by the appended claims.

We claim:

1. In a locker door, a reinforcement extending adjacent one edge of the door and shaped to provide a vertical guide housing, a manually operable latch bar mounted for vertical movement in said housing, latch bolt guides secured to said bar, and latch bolts slidably engaging said guides and movable longitudinally of the bar under spring tension.

2. In a locker door, a sheet metal reinforcement adjacent one edge of the door shaped to define a longitudinally extending guide housing, a manually operable substantially channel-shaped sheet metal latch bar mounted for longitudinal movement in said housing, latch bolt guide members secured along the length of said bar, latch bolts mounted for longitudinal movement along said guides, and spring means for normally urging the latch bolts towards latching position.

3. Latching and lock mechanism for lockers having a door formed with a sheet metal reinforcement adjacent one edge thereof shaped to define a longitudinally extending guide housing, comprising a substantially channel-shaped latch bar mounted for longitudinal movement in said housing, a series of latch bolts secured along the length of said bar and movable under spring tension into latching position independently of the bar, a lift bar connected to said latch bar and projecting through a slot in the door whereby the latch bar may be moved vertically together with said bolts to unlatch the door, a door handle formed with a depending skirt portion having a recess therein into which the lift bar moves when the latch bar is raised to unlatching position and an undercut to provide clearance for the finger of an operator when the lift bar is raised, the lift bar being formed with an opening in the area of the undercut to receive a padlock.

4. In a locker door, a sheet metal reinforcement adjacent one edge of the door shaped to define a longitudinally extending guide housing, a

- substantially channel-shaped sheet metal latch bar mounted for longitudinal movement in said housing, a series of latch guides secured along the length of said bar, latch bolts mounted for longitudinal movement along said guides independently of the latch bar and having their upper ends formed with a stop to limit their downward movement along said guides, and springs connecting said bolts with the guides for normally urging the bolts downwardly towards latching position in said guides. 5
5. In a sheet metal locker having cam surface latch hooks and having a door formed with a longitudinally extending reinforcement and guide housing adjacent one edge thereof, latching mechanism comprising a substantially channel-shaped sheet metal latch bar mounted for longitudinal movement in said housing, latch bolt guides connected to the bar, latch bolts mounted for longitudinal movement along said guides, springs for normally urging said latch bolts towards latching position, said bolts being disposed adjacent said latch hooks and arranged to automatically move into latching position when the door is closed, a door handle, and a finger lift bar connected to the latch bar and projecting through a slot in the door adjacent said handle whereby the latch bar may be moved bodily carrying the bolts therewith when it is desired to unlatch the door. 10
10. In a sheet metal locker having cam surface latch hooks and having a door with the metal adjacent one edge thereof shaped to define a longitudinal reinforcement and guide housing, latching mechanism comprising a substantially channel-shaped latch bar mounted for vertical movement in said housing, latch bolt guides connected to said bar, a lip on each guide bent outwardly therefrom, latch bolts mounted along the length of said bar and arranged to move vertically independently of the bar, a lip on each latch bolt bent outwardly therefrom, a spring intermediate said lip on said bolt and said lip on said latch bolt guide for normally urging said bolts towards latching position, said bolts being disposed adjacent said latch hooks and arranged to automatically latch when the door is closed, a handle connected to said door, and a lift member connected to said latch bar and projecting through a slot in said door adjacent said handle to provide for bodily moving the latch bar vertically to release the bolts and unlatch the door. 15
15. In a locker, a door, a latch bar manually movable longitudinally along one edge of the door, latch bolt guides secured to said bar, and latch bolts slidably engaging said guides and movable longitudinally of the bar under spring tension. 20
20. In a locker, a door, a latch bar manually movable longitudinally along one edge of the door, latch bolt guides secured to said bar, and latch bolts slidably engaging said guides, the bolts and bar being movable manually in one direction longitudinally of said bar and the bolts being movable independent of the bar under spring tension in the opposite direction. 25
25. In a locker, a door, latch bar slidably mounted along one edge of the door, latch bolt guides secured to the bar, and spring pressed latch bolts slidably engaging said guides, the bolts and bar being movable manually in one direction longitudinally, the bolts being movable independently of the bar, in one direction against the spring tension. 30
30. In a locker, a door, a latch bar slidably along one edge of the door, latch bolt guides secured to the bar, and spring pressed latch bolts slidably engaging said guides, the bolts and bar being movable manually in one direction longitudinally, the bolts being movable independently of the bar under spring tension, a handle for the door and means for lifting the bar. 35
35. HENRY C. BAKER.
ROBERT H. PETERSON. 40
